UNITED STATES PATENT OFFICE.

WILLIAM H. GOLDSBERRY, OF NEVADA, IOWA.

TAILOR'S SQUARE.

SPECIFICATION forming part of Letters Patent No. 247,339, dated September 20, 1881.

Application filed March 29, 1881. (No model.)

To all whom it may concern :

Be it known that I, WILLIAM H. GOLDSBERRY, of Nevada, in the county of Story and State of Iowa, have invented an improved 5 drafting-square and method of applying, adjusting, and operating graduated scales in drafting garments, of which the following is a specification.

The object of my invention is, first, to facilitate the drafting of coats, pants, vests, dresses, and all kinds of garments that can be marked out, cut, and fitted by actual measurement; second, to provide a means for folding the two arms of a square into parallel position, for the 15 purpose of packing it more compactly and handling and preserving it when not in use.

It consists in permanently and adjustably connecting two slotted arms to form a right angle and square by means of a rigid strap that constitutes an invariable hypotenuse and brace in 20 the square, in such a manner that the overlapping ends of the two arms at the angle or corner of the square can be readily locked together by means of a thumb-screw to produce 25 a rigid square, to which graduated scales can be successively attached and adjusted from one arm of the square to the other in forming scales in such a manner as to be adapted to be used in combination with the improved square, 30 all as hereinafter fully set forth.

Figure 1 of my accompanying drawings shows my square in an inverted position and its two arms folded in parallel position, as required for convenience and safety in packing 35 and shipping, and in placing it in a drawer when not in use. Fig. 2 is a top view, showing the arms extended at right angles to each other and rigidly locked together and braced, as required for practical use. Fig. 3 represents one 40 of a series of graduated scales designed to be used in combination with the square. Fig. 4 is the diagram of the front part of a vest drafted by means of my improved square and one of my adjustable scales. Jointly considered, these 45 figures clearly illustrate the construction, operation, and utility of my complete invention.

A is the long arm of my folding square. It is preferably made of hard wood, twenty-four (24) inches in length and about one (1) inch in 50 width. At its inner and square end it is about

one-fourth ($\frac{1}{4}$) of an inch thick, and has a square shoulder formed thereon on its top side, adapting it to overlap and engage the corresponding end of a short arm, as required to produce a rigid right-angled joint.

B is the short arm, preferably about eighteen (18) inches long and three-fourths of an inch wide.

c is a metal strap pivoted to the under sides and inner ends of the arms A and B in such a 60 manner that they are thereby permanently and also adjustably connected, as required to produce a rigidly-braced square, when the ends of the arms are overlapped and locked together by means of a thumb-screw, d, that is passed 65 downward through a perforation, f, in the end of the arm B, and into a screw-seat, g, that is fixed in the end of the arm A.

h is a longitudinal slot in the central portion of the arm A. 70

i is a longitudinal slot in the outer portion of the arm B. The edges of these slots are rabbeded on their under sides to allow the heads of short screw-bolts to traverse them while the square lies flat upon the drafting-table, as required to move said bolts k in said slots relative to the ends of the scales that are to be fastened to the arms of the square. 75

m is one of my series of graduated scales, adapted to be adjustably connected with my 80 folding square. They are preferably made of thin strips of flexible hard wood and a complete scale is marked on each side of each piece by means of dies, types, or in any suitable way. It has a perforation, r, at the end designed to 85 be pivoted to the corner of the square by means of the thumb-screw d, that connects and locks the ends of the arms A and B together. It also has a notch, s, at its opposite end, that allows a sliding screw-bolt, k, to engage the 90 scale in such a manner that a thumb-nut, w, on the end of the bolt can be turned down to clamp the scale to the slotted arm of the scale, as shown in Fig. 2. By means of the slots in the arms of the square, the notches in the ends 95 of the scales, and the sliding screw-bolts in the said slots, scales of different lengths can be readily fastened to the square, and also, when pivoted at the corner of the square, readily adjusted from one arm to the other, as fre- 100

quently required in drafting garments, and as indicated by dotted lines in Fig. 4.

In the practical operation of my invention, I take one of my series of graduated scales, that corresponds in number with the breast-measure or circumference of the person for whom a garment is to be drafted, and attach it to the long arm of the square. For example, to draft a vest to fit a boy that measures twenty-four (24) inches around his breast, I use the scale marked 24 across its end. I place the square, with the scale attached, on the cloth upon which I wish to form my diagram, as directed by a pattern-sheet, in such a manner that the outside edge of the long arm will rest upon and be parallel with the edge of the material inside of the selvage, and the short arm will extend laterally over the same material. I then draw a line along the outside edge of the square. On a base-line thus obtained I locate and mark the points designated by the pattern-sheet by means of corresponding numbers on the scale. When a point and number higher than 10 is to be located and marked the square can be readily shifted to start again at the point 10, where the scale ended, so that any number and point varying between 10 and 20 can be located by means of the same scale in the same direct line. To mark or locate a number and point higher than 20, the square can be again advanced along the same line to the point marked 20, and any point and number varying between 20 and 30 located by means of the same scale; and when all the various points on the edge of the pattern-sheet are thus copied,

located, and marked along the edge of the cloth, I loosen the notched end of the scale and turn it on the pivotal screw in the corner of the square from the long arm to the short arm that extends across the cloth, and use the same scale for locating and marking the various points required to be made relative to the baseline and the points previously marked on that line, as illustrated by Fig. 4, and as commonly practiced in the art of drafting garments by means of scales.

Each one of my series of graduated scales is divided into ten (10) equal tenths and fractions thereof. Scales consisting of an equal number of twelfths or other equal divisions may be used in combination with my square.

I claim as my invention—

1. The improved drafting-scale composed of the long arm Δ , having a slot, h , and a screw-seat, g , the short arm B , having a slot, i , and perforation f , the pivoted strap and brace e , the thumb-screw d , and the sliding screw-bolts $k w$, substantially as shown and described, to operate in the manner set forth, for the purposes specified. 60

2. The adjustable scale mrs , in combination with the scale $A B$, having slots $h i$, a thumb-screw, d , and sliding screw-bolts $k w$, substantially as shown and described, to operate in the manner set forth, for the purposes specified.

WILLIAM H. GOLDSBERRY.
